(57) **CLAIM**

The ornamental design for a camera stabilizer, as shown and described.

DESCRIPTION

FIG. 1 is a front side perspective view of a camera stabilizer according to the claimed design;

FIG. 2 is another side perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view thereof in a condition of use state with a tripod.

The broken lines shown depict environmental subject matter and form no part of the claimed design.
